UNITED STATES PATENT OFFICE.

ARTHUR L. HALLIDAY, OF YONKERS, NEW YORK, ASSIGNOR TO THE
BIGELOW CARPET COMPANY, OF CLINTON, MASSACHUSETTS.

DESIGN FOR A CARPET.

SPECIFICATION forming part of Design No. 12,503, dated October 4, 1881.

Application filed August 25, 1881. Term of patent 3½ years.

To all whom it may concern:

Be it known that I, ARTHUR L. HALLIDAY, of Yonkers, in the county of Westchester and State of New York, have invented a new and original Design for Carpets, of which the following is a specification.

This invention relates to a new and original design for carpets and similar fabrics; and it consists in the novel grouping and configuration of parts, hereinafter more fully described.

The accompanying photograph illustrates a face view of a carpet having my new design.

A and D are the two prominent subdivisions of the carpet, which are separated by an ornamental band. The part D has a lower border, b, which is composed of leaf-like ornaments placed side by side, with V-shaped figures placed between their pointed ends. Above the border b is an undulating stripe, above which are the figures B and C. The figure B resembles a large cluster of leaves and has branches a at its sides. The figure C is a richly-ornamented leaf, with slender branches projecting from its upper part, and from its sides. The part A of the carpet consists of two stripes, c and d. The stripe c is ornamented with rosettes and intervening three foils, and the part d is ornamented with leaf-like figures similar to those contained in the stripe b, but it has not the V-shaped ornaments between the leaves. The upper part of the stripe d is com-

posed of series of vertically-placed bars, as shown.

I claim—

1. The design for carpets, consisting of the figure b, substantially as shown.
2. The design for carpets, consisting of the figure B, having ornament a, substantially as shown.
3. The design for carpets, consisting of the figure C, substantially as shown.
4. The design for carpets, consisting of the figure B, having ornament a, figure C, and undulating stripe, substantially as shown.
5. The design for carpets, consisting of the figure B, having ornament a, figure C, undulating stripe, and border b, substantially as shown.
6. The design for carpets, consisting of the figure c, substantially as shown.
7. The design for carpets, consisting of the figure d, substantially as shown.
8. The design for carpets, consisting of the figures c and d, substantially as shown.
9. The design for carpets, consisting of the figure B, having ornament a, figure C, undulating stripe, border b, and stripes c and d, substantially as shown.
